NEUTRALIZATION OF CAVITY TYPE HIGH FREQUENCY AMPLIFIER

Theo W. Williams, Buffalo, N. Y., assignor to the United States of America as represented by the Secretary of the Army

Application June 15, 1954, Serial No. 438,889

2 Claims. (Cl. 179—171)

This invention relates to an improved method of neutralizing a radio-frequency amplifier of the reentrant cavity type.

Ordinarily cavity type radio-frequency amplifiers are neutralized by means of inductive loops or capacitive probes which feed back out-of-phase voltage from the anode to the control grid. These methods are often cut-and-try and do not readily lend themselves to cavity construction. Furthermore, these methods require critical adjustments and such adjustments are difficult to make using loops or probes.

Accordingly, it is an object of this invention to provide an improved neutralization scheme not subject to the above difficulties.

In accordance with the present invention, one or more apertures or slots are placed in the common wall of the grid and plate cavities of a coaxial cavity type radio-frequency amplifier, these apertures being positioned relatively close to the tube. A conductive member coaxial with the wall is then positioned over the apertures. The member is adjustable from without the cavity so as to control the effective size of the apertures and thereby control the amount of out-of-phase neutralizing energy fed from the anode cavity to the grid cavity.

The features of the invention which are believed to be novel are set forth in particularity in the appended claims. The invention itself, however, both as to its organization and method of operation, can best be understood by reference to the following description taken in conjunction with the accompanying drawing, in which:

Figure 1 is a cross-sectional view of a reentrant cavity type radio-frequency amplifier;

Figure 2 is a cross-sectional view along line 2—2 of Figure 1.

Referring now to the drawing, there is shown a triode 11 comprising a cathode 12, grid 13 and anode 14. An anode line 15 which forms the outermost wall of the cavity structure is connected directly to the anode. Line 16, which forms the common grid-anode cavity wall, is coupled through dielectric rings 23 to the grid 13, and cathode line 17 is coupled through dielectric ring 22 to the cathode 12. To provide out-of-phase feed back from the anode cavity 28 to the grid cavity 27, a plurality of apertures 18 are placed in the common wall 16 close to the tube 11. The effective size of the aperture openings is controllable by means of a conductive ring 20 positionable over the slots by means of an insulated rod 21 which extends without the cavity structure. Means, not shown, such as a knob and gearing arrangement, may be provided for vernier control of the ring position. A ring of dielectric material 19 is fastened to the conductive ring 20 so as to provide a high degree of capacitive coupling between

2

ring 20 and wall 16. In order to tune the cavities, plungers 25 and 26 which are adjustable axially of the length of the cavities, are provided. The anode line 15 is grounded and the cathode 12 is maintained at a negative potential through lead 24 which is connected to B minus.

Although not shown in the drawing, it is to be understood that the triode 11 is provided with a filament for heating the cathode thereof and that leads within line 17 are provided for supplying heater current to the filament.

10 Also, although not shown, means are provided for supplying an input signal to the grid of the triode and means are also present for deriving a usable output from the amplifier structure. The latter may comprise, for example, a loop or probe coupled into the anode cavity and, similarly, the signal input to the control grid may comprise a loop or stub coupled into the grid cavity. Finally, although not shown, a D.-C. return path is provided for the grid.

While there has been described what is at present considered a preferred embodiment of the invention, it will be obvious to those skilled in the art that various changes and modifications may be made therein without departing from the invention, and it is aimed in the appended claims to cover all such changes and modifications as fall within the true spirit and scope of the invention.

What is claimed is:

1. A high-frequency amplifier comprising a triode, a first conductive member coupled to the cathode of said triode, a second conductive member coaxial about said first member coupled to the control grid of said triode, a third conductive member coaxial about said second member coupled to the anode of said triode, the space between said first and second members defining a first cavity resonator and the space between said second and third members defining a second cavity resonator, said second member being provided with a plurality of slots transverse to the longitudinal axis and close to the end thereof to allow feed-back therethrough of out-of-phase energy from said second resonator to said first resonator for neutralizing said amplifier, a member of dielectric material positioned to cover said slots, a flat ring of conductive material encircling said dielectric material, a dielectric rod fastened to said ring and extending external to said resonator for axially moving said ring to provide adjustment of the effective size of said slots.

2. A high-frequency amplifier comprising an electron discharge device having a plurality of enclosed electrodes including an anode, a cathode and a grid, a plurality of substantially concentric members connected respectively to said electrodes and defining anode-grid and grid-cathode space resonant regions, the intermediate concentric member being provided with a plurality of transverse slots for feeding back out-of-phase energy from the former to the latter space resonant region for neutralizing said amplifier, a concentric dielectric member positioned to cover said slots, a cylindrical member of conductive material adjustably fastened to the surface of said dielectric member and means extending externally for adjusting said last named cylindrical member to permit variation of the effective size of said slots.
